CLAIM

The ornamental design for a non-contact type data reader, as shown and described.

DESCRIPTION

FIG. 1 is a rear elevational view of a first embodiment of a non-contact type data reader showing our new design;

FIG. 2 is a right side elevational view thereof, a left side elevational view thereof being a mirror image; and

FIG. 3 is a top plan view thereof, a bottom plan view thereof being a mirror image.

FIG. 4 is a front elevational view of a second embodiment of a non-contact type data reader showing our new design; FIG. 5 is a right side elevational view thereof, a left side elevational view thereof being a mirror image; and, FIG. 6 is a top plan view thereof, a bottom plan view thereof being a mirror image.

The broken lines illustrating unclaimed portions of the non-contact type data reader form no part of the claimed design.
